UNITED STATES PATENT OFFICE

HARRY F. GEPhART, OF CHICAGO, ILLINOIS

DESIGN FOR AN ADVERTISING FISHING-ROD DISPLAY STAND

Application filed May 20, 1930. Serial No. 35,699. Term of patent 7 years.

To all whom it may concern:

Be it known that I, HARRY F. GEPhART, a citizen of the United States, residing at Chicago, in the county of Cook and State of Illinois, have invented a new, original, and ornamental Design for an Advertising Fishing-Rod Display Stand, of which the following is a specification, reference being had to the accompanying drawing, forming a part thereof.

In this drawing:—

Figure 1 is a front elevational view of the article showing my new design, which consists of a stand having means to hold a fishing-rod which is to remain intact as constituting a part of the entire article.

I claim the ornamental design for an advertising fishing-rod display stand, as shown and described.

HARRY F. GEPhART.
